[57] CLAIM

The ornamental design for a combined monkey figure and wheel chair, substantially as shown and described.

DESCRIPTION

FIG. 1 is a frontal perspective view of a combined monkey figure and wheel chair, showing my new design;

FIG. 2 is a rear perspective view of a combined monkey

FIG. 3 is a top plan view thereof; and

FIG. 4 is a bottom plan view of a combined monkey
